UNITED STATES PATENT OFFICE.

RICHARD H. STRASSER, OF WASHINGTON, DISTRICT OF COLUMBIA.

INDOOR GOLF SYSTEM.

Application filed November 25, 1922. Serial No. 603,271.

To all whom it may concern:

Be it known that I, RICHARD H. STRASSER, a citizen of the United States, residing at Washington, in the District of Columbia, 5 have invented a certain new and useful Improvement in an Indoor Golf System, of which the following is a specification.

My invention relates broadly to the game of golf and more particularly to a system 10 for playing the game of golf for instruction, practice, exercise and amusement in restricted areas indoors simulating the conditions which occur on a regulation course.

One of the objects of my invention is to 15 provide a system for playing the game of golf indoors whereby drives may be made from tee to green indoors under conditions which prevail over a regulation course without regard to weather conditions and ex- 20 posure.

Another object of the invention is to 25 provide an arrangement of golf meters for simulating the drives made over a regulation course with such hazards as bunkers and sand traps adjacent the golf meters, and greens adjacent the machines whereby long drives may be made on the machines and shorter drives may be made over the hazards and the ball putted on the green for 30 completing the hole.

Another object of the invention is to provide an arrangement of golf meters, hazards, 35 sand traps and greens within an enclosed area whereby a number of players may be accommodated in playing the game of golf simultaneously without interference or confusion.

A further object of the invention is to 40 provide an arrangement of indoor golf apparatus whereby the indoor area allowed for the game may be divided in such manner that individual instruction on the golf meter, putting green, sand trap, bunker, and with driving cages, may be given to players 45 in one portion while a plurality of games of golf may be played on golf meters, hazards, and sand traps and greens in another portion of the enclosed area.

Another object of the invention is to 50 provide a construction of bunker, sand trap and green for playing the game of golf indoors with scales and calibrations whereby the drives and strokes may be measured.

Another object of the invention is to 55 provide a chart representation of the holes in a regulation golf course showing distances

from tee to green and hazards within the intervening distance whereby drives may be made on golf meters and over artificial hazards, and the ball putted on the green 60 simulating the course of the ball over the charted course under the actual conditions of the outdoor game.

Other objects of the invention will be understood by reference to the following 65 specification and the accompanying drawings, in which:

Fig. 1 is a plan view of one form of the arrangement of my indoor golf system; Fig. 2 shows a chart representing the drives from 70 tee to green required in playing the different holes of the golf course showing relative distances between tee, hazards, and the green; Fig. 3 is a plan view of the green employed in my indoor golf system; Fig. 4 is a view 75 partially in section taken through the sand trap showing the graduated screen against which drives are made in driving out of the sand trap; Fig. 5 is a cross sectional view taken through the green shown in Fig. 80 3; Fig. 6 is a perspective view of a unit arrangement of golf meter, putting green, sand traps, and bunker employed for individual instruction, practice or play in the game of golf. 85

The object of the game of golf is to drive the ball from the tee to the green in the least number of strokes. Throughout the distance from tee to green are certain hazards both natural and artificial, consisting of trees, streams, bunkers and sand traps. The center of course known as the 90 fairway is especially prepared for playing by maintaining the grass in neatly cut condition, while on the edges it is not prepared 95 for play in that the grass is long—this area is known as the rough.

In order to play the game each player has certain equipment, including clubs comprising among others a driver, brassie, mid-iron, 100 cleek, mashie, mashie niblic, and putter.

In beginning the game on a regulation outdoor course the ball is placed on the tee and driven down the fairway for a distance of a number of yards using the 105 driver. The distance to which the ball has been driven on the first drive will leave the choice of the next club to obtain the balance of the distance at the option of the player until the ball has been driven on the green, 110 when the player would be required to use the putter in completing the play for the hole.

The various clubs are used for making drives of various distances. The mashie and the mashie niblic or similar clubs are used by players in playing from the natural and artificial hazards.

There are several kinds of shots which might occur from the drive, namely; the straight drive, a drive pulling to the left, or a slice drive slicing to the right, and a 10 topped drive which merely rolls off the tee. Hazards with particular references to trees, streams and sand bunkers, occur at various distances between the tee and the green.

In the present invention I provide an arrangement for simulating the conditions prevailing on the outdoor regulation golf course whereby the game may be played for amusement, instruction and practice without regard to weather conditions. A plurality of golf meters or machines measuring a drive usually graduated in hundreds of yards are provided and hazards such as sand traps, bunkers and greens arranged adjacent thereto.

25 The drive made by a player on a golf meter or machine simulating the drive over a natural course is read directly in yards. A chart of the course is placed at each machine to indicate to the player the location of hazards in yards and so advises him the location in distance which the ball has been driven.

In using the type of machine known as the Craig golf meter, the ball and trolley 35 rotate about the fixed upright when the ball is hit by a club; the hand on the dial recording in yards the actual distance of each drive. The flight of the ball through the air indicates whether it has been cleanly 40 hit, topped or "sliced."

The reading on the meter with reference to the chart determines whether the drive has placed the ball in a trap or its location. In this case the player moves to trap. The ball on the machine is secured while the ball played in the trap and on the green is a free ball. The player starts from some convenient point in the trap and attempts to drive out of the sand over the hazard against a calibrated screen. The termination of the drive with reference to a curtain reading which the ball strikes indicates distance in yards the player has driven from trap. When the difference between distance driven from the trap and green is less than a particular limit the player would be deemed to be on the green and would proceed to putt out in the usual manner. The distance between the trap and the screen is graduated or indicated by a scale converting yards to feet on account of playing in confined space, making it impossible to continue the play in yards, while the curtain indicates distance in yards.

65 At times when player drives on machine

and registers such a figure that the corresponding chart would indicate that the player had driven within a limited distance of the green, the player moves direct to green to complete the drive to the hole. 70
The greens are placed convenient to each machine and the distance players are required to putt for the hole is determined by scale in feet representing yards of play. 75
The player locates the ball on the green as determined by reading on the golf machine or on the screen adjacent the trap. The scales convert yards to feet for conserving space.

This indoor course is adapted for playing either medal or match play, as the professional game is always medal play and the amateur game match play. 80

By use of the above equipment it is quite practical to play the game of golf indoors under exactly the same conditions as occur on a regulation course. The players use standard clubs and drive standard golf balls and exert as much energy in hitting the ball secured to the golf meter as they would ever care to expend in an actual drive on the course. The drive gives the chief thrill to the player in the game and it has been taken care of on the golf meter, except that the ball instead of going straight away revolves around the golf meter. If a perfect drive is made the ball will rise to the top of the machine and register the number of yards on a dial. The golf meter is especially adapted to the use of iron clubs, with the exception of the putter, as putting is approximately one-third of the entire game. The putting greens adjacent to each machine provide a method of completing the exact distance required for any given number of yards per hole.

Referring now more particularly to the drawing, Fig. 1 illustrates one form of arrangement of my indoor golf system wherein reference characters 1 to 9 represent golf 110 meters arranged in a row, and numerals 10 to 18 represent another row of golf meters on an opposite side of a building. The building may take many different forms such as square, rectangular, hexagonal or circular, 115 but in the arrangement illustrated the enclosure 20 is shown in rectangular form. Each unit for making long drives simulating drives of hundreds of yards over a regulation golf course comprises the golf meter 120 1, a mat 1^a serving as a tee which may be a cocoanut mat and a mat 1^b which may be a rubber mat on which the player may stand. Each unit is separated from an adjacent unit by a suitable partition 21, 22, and so on. 125 A partition 24 divides the area 20 into a professional player's unit for individual instruction and the portion of the building which includes the rows of machines. The individual instruction room includes the golf 130

meter 18, the mat 18^a serving as a tee, the mat 18^b on which the player may stand, the putting green 18^c, the sand trap 18^d, and hazard comprising the bunker 18^e. The entire game of golf may be played within this partitioned area 24. Within the area 20 and placed intermediate the rows of machines the driving cages 25 are arranged. These cages comprise two portions with screen 38 (Fig. 4) placed vertically between the sand traps 26 and 31, each of which are constructed in combination with bunkers 27 and 32. Each of the driving cages is provided with a scale indicated at 28 and 30 to permit the ready location of the ball with reference to the sand trap and bunker. In the space intermediate the rows of machines the greens 34 and 35 are arranged on the surface 20. Aisles are left free for the passage of players from the various machines to the sand traps and to the greens.

Fig. 2 represents a chart indicated by reference character 50 of the different holes in a regulation golf course each played from tee to green showing the locations of hazards and the distances intervening between the tees and hazards and the green in driving from each tee to the corresponding hole. This chart will indicate the drives and strokes required in playing each hole. The representation for hole #1, for example, shows tee 51, hazards 52 and 53, and green 54, with the intervening distances expressed in yards.

Figs. 3 and 5 illustrate in more detail the construction of the green. The green is placed on supporting surface 20 and is formed of a filler 46 having a rolling surface with the periphery extending at a higher plane 48 than the body portion thereof. The surface of the filler may be covered smoothly with heavy material such as velvet or plush rugs, or material to provide a similar surface at 45. Calibrated scales 39 and 40 are arranged on the sides of the greens. The green is provided with stations 1 to 9 as indicated at 41 and 42 from which players may play out to the holes. The holes are indicated at 43 and 44. The surface of the green is rolling in form as indicated by the wavelike lines in Fig. 3. The distance between the holes and the starting stations from which the players move is represented by the straight lines adjoining the holes and the stations. It is understood that these lines are merely theoretical and do not appear on the green.

In Fig. 4 the screen 38 within the driving cages 25 is graduated to represent drives which are made out of the sand trap 26 over the bunker 27. These graduations indicate distances in yards obtained by drives over the hazard. The section through the sand trap and bunker shows the filler 36 which may be a clay base or other material covered

with several inches of loose sand and cocoa mats or other material securely fastened in place over the surface.

In Fig. 6 the portion of enclosure 20 partitioned off at 24 is represented in perspective. In this room a professional may give individual instruction to a player who drives on the golf meter 18 when standing on mat 18^b. The mat 18^a forms the tee from which the ball is driven. The green 18^c is arranged adjacent the machine, and adjacent the green a hazard is placed comprising the sand trap 18^d and a bunker 18^e. A graduated curtain may be arranged on the wall adjacent the bunker whereby drives out of the sand trap 26 may be measured as indicated in Fig. 4. The room may be used for instruction and practice purposes without the graduated curtain.

In playing contests on the golf meter as an amusement, from two to four players may use a single machine. In starting to play a match of nine or eighteen holes, players are provided with a score card as shown in Fig. 2 indicating hole #1 as 400 yards from tee to green. The player will take the driver and drive the ball from the tee 1^a. If a fairly struck ball results a drive of 200 yards should be recorded on the meter, leaving a distance of 200 yards. The player now has the option of using either a mid-iron or brassie; by the use of the brassie and a fairly struck ball the meter would indicate a distance of 100 yards, leaving 100 yards to the green. The player again has the same opportunity in making a choice of clubs for this short distance the mashie, cleek, niblic, mashie niblic and jigger. A player making any distance between 25 yards and the green would be considered to be on the green 25 feet from the hole and would proceed to putt out from that distance on the green. If however the player's drive should register 140-150 yards or 240-260 yards, the player would have driven into a sand trap. It would then be necessary for the player to go to the sand trap 26 and there properly drop a ball and proceed to play out of the trap guided by the scale graduations exactly as on a regular course. The distance made by a player from a sand trap is indicated by the ball striking the curtain 38 upon which is laid out the distance in yards. A fair-out striking the curtain in the center not too high or too low would allow the player the average distance obtained from drives of this nature. The diagram of the entire course of eighteen holes would be placed in a convenient location at each machine upon which would be indicated all hazards, bunkers and traps. On a bad slice or hooked ball, the player would have to consider the ball to have been driven off the fairway into the rough or long grass and would be required to play an iron club on the next

stroke. The representations on the chart may be made to simulate and correspond with the layout of holes in the finest golf courses in the world.

5. The invention upon which this application is based is broader than the specific embodiment thereof which has been shown for the purpose of illustrating one of its arrangements, and I intend no limitations other than 10 those imposed by the appended claims.

What I claim and desire to secure by Letters Patent of the United States is:

1. A method of playing a game simulating golf which comprises driving a ball associated with a golf meter, comparing the reading of said golf meter with a chart of a golf course indicating the location of the ball on said course relative to traps and hazards as a result of said drive, and completing the 20 drive of the ball over said traps and hazards relative to said chart with a free ball.

2. A method of playing an indoor game of golf comprising driving a ball operatively connected with a golf meter, comparing the 25 reading of said meter with a chart of a golf course, driving a free ball over hazards and a green simulating hazards and green on said chart, driving long distances on said golf meter and short distances over said 30 hazards and on said greens.

3. In a system for playing the game of golf indoors, the combination of a plurality of machines including a confined ball for simulating distances of drives over a natural 35 course, hazards and greens adjacent said machines whereby drives of many yards may be made on said machines with said confined ball and drives of shorter distances may be made with a free ball over said hazards and 40 on said greens.

4. A method of playing the game of golf indoors, which consists in driving a confined ball about a golf meter whereby distance simulating a drive over a natural golf 45 course is measured, and utilizing a free ball for intermediate strokes over shorter distances dependent upon the indications of said golf meter.

5. In a system for playing the game of golf indoors, the combination of a plurality of machines for measuring the distance of drives of a confined ball simulating drives 50 on a natural golf course, hazards adjacent said machines, artificial greens adjacent said 55 hazards, whereby long drives may be made on said machines with said confined ball and intermediate strokes over said hazards and on said greens with a free ball.

6. In a system for playing golf indoors, 60 an artificial green including a plurality of holes, a rolling surface on said green, a plurality of stations for playing each hole, a graduated chart of a natural golf course and scales on the sides of said green corresponding 65 to scales on said chart whereby a player

may locate a ball for putting out for said holes in accordance with said chart.

7. In a system for playing golf indoors, the combination of a plurality of rows of machines each including a confined ball for simulating drives of a ball over a given course, a plurality of hazards and sand traps between said rows of machines, and greens between said rows of machines whereby players can drive confined balls on said machines simulating drives of relatively long distances over a golf course and play intermediate strokes over said hazards and short strokes on said greens, said latter strokes being made with a free ball. 75

8. In a system for playing the game of golf indoors, the combination of a plurality of machines calibrated to simulate drives over a natural golf course in hundreds of yards, sand traps having calibrated vertical screens adjacent thereto whereby the distances of drives of a free ball over said traps may be indicated, a chart representing distances over a natural golf course whereby a player may determine the location of his 90 drives at all times, and an artificial green calibrated for putting to a hole when a player arrives in proximity to the hole by drives on said machines and over said sand traps. 95

9. In a system for playing the game of golf indoors, the combination of a plurality of rows of machines including a confined ball for simulating the drive of a golf ball over a natural course in hundreds of yards, a plurality of sand traps and artificial greens intermediate said rows of machines, and a unit assembly separate from said machines, sand traps and greens comprising a separate machine having a confined ball, a sand trap and a green intermediate said separate machine and sand trap whereby the entire game of golf may be played simultaneously in said unit and on said rows of machines simulating the actual drive of a golf ball 100 from tee to green in actual courses. 105

10. In a system for playing the game of golf, the combination of a machine including a confined ball for simulating the drive of a golf ball over long distances, an artificial green adjacent said machine, a sand trap adjacent said green whereby strokes of hundreds of yards may be played on said machine with said confined ball and shorter strokes may be played in said trap and on 110 said green with a free ball. 115

11. In a system for playing the game of golf indoors, the combination of a plurality of machines each including a confined ball for simulating the drive of a ball over distances of hundreds of yards, sand traps and artificial greens adjacent said machines whereby strokes of shorter distances may be played over said sand traps and said artificial greens with a free ball. 120 125

12. An apparatus for playing the game of golf indoors having a progressive series of golf meter machines each including a confined ball for simulating the drive of a ball to different holes in a natural course, the machines being arranged with an aisle adjacent the sides thereof with artificial hazards and greens on the opposite side of said aisle whereby a player may drive to one hole in the course on one of said machines using said confined ball and complete the drive over said artificial hazards and greens using another ball and progress to adjacent machines to play succeeding holes in the course. 45
13. An apparatus for playing the game of golf indoors comprising a series of golf meters each including a confined ball arranged to be driven for simulating the drive of a golf ball over differently charted courses, hazards and greens adjacent said machines whereby players may drive a ball on one of said machines simulating a drive over a charted course and complete the drive over hazards and greens with a free ball and then progress to an adjacent machine and drive over a differently charted course completing the drive over said hazards and greens with a free ball, and similarly progressing on said machines, hazards and greens for differently charted holes to play the entire game of golf. 50
14. A building for playing the game of golf indoors, including a large aread room having partitions dividing the room into a plurality of portions each portion including a golf meter having a confined ball, a sand trap, hazard and green, a chart for each portion representing a graduated plan layout of a natural golf course, said golf meter, sand trap, hazard and green being arranged for simulating drives of said confined ball over distances of hundreds of yards in accordance with each of said charts, 55
- an aisle in each portion, whereby players may progress from one of said golf meters playing long strokes with said confined ball to said artificial hazards and greens and completing a drive with a free ball, and then progressing to another golf meter and succeeding golf meters to play the entire game of golf. 60
15. In a system for playing the game of golf indoors, an artificial green comprising a supporting surface, a filler having a plurality of recesses therein carried by said supporting surface, a covering extending over said filler and arranged as a lining for said recesses, and means about the periphery of said filler whereby said covering has one portion thereof in a plane at a higher level than another portion thereof for confining a free ball on the green, and an irregular surface throughout said last named portion. 65
16. In a system for playing the game of golf, a chart representing the distances of drive from tee to green for a plurality of different holes in an actual course, a series of machines for simulating drives in hundreds of yards over said courses, and a plurality of greens, sand traps and hazards for completing drives for each of said holes comparable with the travel of a ball over each of said courses from tee to green, and calibrations on said chart corresponding with calibrations of drives on said machines, sand traps, hazards and greens. 70
17. In a system for playing the game of golf indoors, the combination of a supporting surface, a bunker carried by said surface, a sand trap adjacent said bunker, calibrations for locating a ball relative to said sand trap and bunker whereby drives may be made over said combined sand trap and bunker simulating drives over a natural golf course in accordance with said calibrations. 75

RICHARD H. STRASSER.
